Primary Examiner — Derrick Holland*Assistant Examiner* — Lauren Calve(74) *Attorney, Agent, or Firm* — Southeast IP Group,
 LLC.; Thomas L. Moses; Randolph J. Tucker(57) **CLAIM**

I claim the ornamental design for a pill card, as shown and described.

DESCRIPTION

FIG. 1 is a front elevation view of a pill card according to my design.

FIG. 2 is a back elevation view thereof.

FIG. 3 is a top plan view thereof.

FIG. 4 is a bottom plan view thereof.

FIG. 5 is a left side elevation view thereof; and,

FIG. 6 is a right side elevation view thereof.

The broken lines that abut a claimed surface represent an unclaimed boundary between claimed and unclaimed surfaces. None of the broken lines form any part of the claimed design.
